UNITED STATES PATENT OFFICE.

AUGUST W. ZERATSKY AND WILLIAM V. KIDDER, OF LA CROSSE, WISCONSIN.

AIR-SUPPLY CONNECTION FOR CARBURETORS.

Application filed December 13, 1920. Serial No. 430,169.

Our invention relates to improvements in air supply connections for carburetors. More particularly, our invention relates to that form of air supply connection which 5 is adapted to supply warm air to the carburetor, thereby promoting more perfect carburetion.

The object of our invention is to provide a carburetor air supply connection which 10 may be attached to the carburetor in the place of the tube previously used; and which, when so attached will rapidly absorb heat from the exhaust manifold and distribute this heat in such a manner 15 that it will be readily absorbed by air passing thru the duct thereby promoting a more perfect atomization and mixture of the gasoline and air; and which will therefore by elimination of waste reduce the quantity 20 of gasoline needed to secure proper combustion in the engine cylinder.

Another object of our invention is to provide an air supply connection such that it can replace those now in use and which when 25 thus substituted will utilize the heat of the exhaust gases to warm the air more effectively than has heretofore been possible.

Another object of our invention is to provide an air supply connection which will 30 increase the velocity of air entering the carburetor and give it a whirling motion which will tend to increase the facility with which such air will take up the gasoline and produce a correct mixture.

Another object of our invention is to provide an air supply connection through which the air will enter the carburetor at a substantially 35 constant velocity regardless of the structure of the carburetor with which our invention is associated.

In the drawings:

Figure 1 is a side view of an ordinary internal combustion engine with my air admission means connected to the carburetor.

Fig. 2 is an axial sectional view exposing the interior of my improved air supply connection.

Like parts are identified by the same reference characters throughout the several views.

The engine block 1 is provided with an intake manifold 2, carburetor 3, and exhaust manifold 4 in the usual manner. The improved air supply pipe comprises simply an L-shaped tube 10 with a bulbous enlargement

11 and end 12 adapted to be inserted into 55 the inlet of the carburetor. An annular flange 13 gauges the depth of insertion. At its upper end, the wall at the inner side of the tube is cut away and the outer side 19 of the tube is flattened to have a bearing 60 upon the exhaust manifold 4. As will be hereinafter explained, this contact allows the heat of the exhaust to be conducted by the metal walls of the tube to warm its whole length. Within the tube and just above 65 bulbous enlargement 11 above referred to, is a cross arm 20 provided with an aperture 19' within which the stem 21 of valve 22 is adapted to slide axially of the tube. At its upper end, the valve stem is provided 70 with a pin 23 and washer 24 which forms a seating for spring 25, the other end of which bears upon the cross arm which supports the valve. It will be noted that the valve is materially less in diameter than the tube 75 within which it is placed. It will also be noted that as the valve moves downwardly against the pressure of the spring, it moves into the bulbous enlargement 11, thereby increasing the area of the space between the 80 valve and the wall of the tube.

This open space surrounding the valve is preferably large enough to permit the passage of all the air needed by the engine at 85 low speeds. But when the engine speed becomes greater and the degree of vacuum in the carburetor increases, the air will rush through our improved supply connection with increased speed and its greater impact upon the valve 22 will cause the valve to 90 open into the enlarged portion 11 of the tube. As soon as the valve moves the space available for the passage of air is greatly increased and the velocity of the air is of course correspondingly reduced. Thus the 95 air valve 22 tends to keep the velocity of air entering the carburetor constant.

Within the tube adjacent to the end 12 which is inserted in the carburetor, we provide a series of helical fins or flanges 15 100 which are of less height than the radius of the tube so that a certain space 16 contiguous to the axis of the tube remains open and unimpeded by the fins. These fins operate to set up a whirling motion in the air passing through the tube.

We have found that by leaving the space 16 open we are able to make the rotative

effect substantially constant. Air coming through the tube 10 at low engine speeds and passing the valve 22 will tend to follow the outside of the curve when it comes to the 5 bend in the tube. Almost all of it will be engaged by the helical fins 15, therefore, and will be given a rotative motion that will tend to keep it next to the wall of the tube. At higher engine speeds when a larger 10 amount of air must move through the tube a large proportion of the air will be drawn straight through the open space 16. This is true because the velocity of the air does not increase proportionately to the volume. 15 It will be remembered that the valve 22 tends to keep the velocity of air flow constant regardless of its quantity. If the velocity were increased, the momentum effects which cause the air to follow the outside of 20 the curve in tube 10 would also be increased and probably most of the greater volume of air would be engaged by the helical fins and would be given a correspondingly increased whirling velocity. But the valve 22 tends 25 to keep the velocity substantially constant and the added volume of air instead of being thrown against outside of the curve in tube 10 will be drawn directly through the central opening 16 where it will not be engaged 30 by the helical fins 15.

Our improved air intake tube may be made of any desired material, but it is preferable to make the tube of aluminum because of the high heat conductivity of that 35 metal. It will be noted that the flattened upper portion of the tube which bears upon the exhaust manifold is designed to take heat from the manifold and if the tube is made of aluminum, the whole length of its 40 walls will be heated by the heat thus obtained. Air passing through the tube will be warmed by the hot walls. The helical flanges adjacent to the carburetor inlet are adapted to impart to the air such heat as 45 still remains unabsorbed thereby. These flanges are purposely made very thin to comprise fins for the purpose of promoting delivery of heat to air traversing the device.

When our improved air inlet is in use, its 50 operation is as follows. The suction produced in the intake manifold 2 of the engine by the movement of the pistons within the cylinder block 1 draws air through the carburetor 3 and through our improved air inlet tube 10. This air taken from the vicinity 55 of the exhaust manifold 4 has already had its initial chill removed so that it enters the tube slightly warm. The aluminum walls of the tube conduct heat rapidly from the 60 exhaust manifold and the air entering the tube rapidly absorbs the heat of the walls especially just before the air reaches the carburetor when it passes between the thin helical flanges or fins 15. These fins, besides 65 giving off heat to the air, impart to it a

rapid whirling motion so that as the air enters the carburetor each particle thereof has not only the ordinary forward speed but has acquired a high velocity in a helical path. 70

The air inlet port of a carburetor is ordinarily circular in cross section so that the whirling motion imparted to the air by the helical flanges 15 will persist after the air enters the carburetor and will cause the air 75 to pass the jets at a much greater velocity than it would have had if it had followed an axial path through the air supply fitting.

It is well known that the vaporization of 80 a liquid hydrocarbon and carburetion of air thereby can be aided materially by increasing the velocity of the air to which the hydrocarbon is exposed. Our invention makes use of this principle by setting the air to whirling as above described. It is important, however, that the velocity of air entering the carburetor shall remain approximately constant so that one adjustment of the carburetor may prove satisfactory for all motor speeds. Our valve 22, and the 85 helical thread 15 with its axial opening 16 work together toward this end.

It will be noted that the valve at no time 90 closes the tube but always permits the passage of air. At slow engine speeds, when the degree of vacuum in the carburetor is not great, the valve will not open at all and such air as passes it is forced through the 95 relatively small area between the circumference of the valve and the inner side of the tube wall. The resistance offered to the passage of the air by this relatively small opening will naturally increase somewhat the degree of vacuum within the carburetor 100 so that when our improved inlet tube is attached to a carburetor, the needle valve will 105 have to be reset to allow for the changed conditions. Once it is set, however, it will need no further attention because as the engine speed increases, tending to produce a 110 higher degree of vacuum within the carburetor, the valve will open into the bulbous enlargement 11 and thereby increase the available area for the passage of air at a 115 rate corresponding to the carburetor requirements so that at all speeds of the engine the air supplied to the carburetor will be under approximately the same degree of pressure.

We are aware that there are carburetors on the market which accomplish substantially 120 this result, but these carburetors do not operate upon the same principle, are ordinarily expensive to construct and consequently sell for high prices and are not standard equipment on the ordinary car. There is, 125 therefore, a great advantage attained by our invention in having a carburetor inlet tube which may be applied to any carburetor and more particularly to the cheaper carburetors of various makes with which low priced cars 130

are equipped and when so applied will make these carburetors the equal, if not the superior, of the more expensive carburetor.

We claim:

- 5 An air inlet fitting adapted to be attached to the inlet ports of internal combustion engine carburetors comprising a metallic tube adapted for contact at its inlet end with a source of heat, adapted for attachment at its delivery end with the carburetor inlet port, and provided intermediate of its ends
- 10

with an enlarged portion, a cross arm within the tube, a valve of less diameter than the tube supported by the cross arm and free to move into said enlarged portion of the ¹⁵ tube, means for resiliently opposing such movements, and a set of helical fins projecting inwardly from the wall of the tube for a portion of its radius at a point adjacent the delivery end of the tube.
